US00D912248S

(12) **United States Design Patent** (10) **Patent No.:** **US D912,248 S**
Yan et al. (45) **Date of Patent:** **** Mar. 2, 2021**

(54) **ENDOSCOPE**

(71) Applicant: **Shenzhen Yateks Optical Electronic Technology Co., Ltd.**, Shenzhen (CN)

(72) Inventors: **Jiangfan Yan**, Shenzhen (CN); **Quan Zhong**, Shenzhen (CN); **Wei Peng**, Shenzhen (CN); **Tianyue Ma**, Shenzhen (CN)

(73) Assignee: **SHENZHEN YATEKS OPTICAL ELECTRONIC TECHNOLOGY CO., LTD.**, Guangdong (CN)

(**) Term: **15 Years**

(21) Appl. No.: **29/552,725**

(22) Filed: **Jan. 25, 2016**

(30) **Foreign Application Priority Data**

Oct. 14, 2015 (CN) 201530395355.0

(51) **LOC (13) Cl.** **24-02**

(52) **U.S. Cl.**

USPC **D24/138**

(58) **Field of Classification Search**

USPC ..... D24/137-138, 108, 22, 117-118, 133, D24/135; 600/145-147, 117, 137, 138, 600/131; D16/130, 132, 136 CPC A61B 1/00; A61B 1/267; A61B 1/2673; A61B 18/1445; A61B 2018/147; A61B 1/00052; A61B 1/0684; A61B 1/00039; A61B 1/0005; G02B 23/2484

(57) **CLAIM**

The ornamental design for an endoscope, as shown and described.

DESCRIPTION

FIG. 1 is a perspective view of an endoscope showing my new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines in FIGS. 1, 4 and 5 show portions of the endoscope that form no part of the claimed design.

1 Claim, 7 Drawing Sheets

FIG.1

FIG.2

FIG.3

FIG.4**FIG.5**
